UNITED STATES PATENT OFFICE.

NANNIE STEPHEN TOLIVER, OF COLUMBUS, TEXAS.

DESIGN FOR A TOY RABBIT.

50,367.

Specification for Design.

Patented Feb. 20, 1917.

Application filed December 21, 1916. Serial No. 138,265. Term of patent 7 years.

To all whom it may concern:

Be it known that I, NANNIE STEPHEN TOLIVER, a citizen of the United States, residing at Columbus, in the county of Colorado and State of Texas, have invented a new, original, and ornamental Design for Toy Rabbits, of which the following is a specification, reference being had to the accompanying drawing, forming part thereof.

Figure 1 is a front view of my toy,

Fig. 2 is a side view thereof, and
Fig. 3 is a rear view thereof.

I claim:

The ornamental design for toy rabbit, as shown.

NANNIE STEPHEN TOLIVER.
